UNITED STATES PATENT OFFICE.

CHARLES A. TIMME, OF NEW YORK, N. Y.

ELECTRIC DENTAL FURNACE.

SPECIFICATION forming part of Letters Patent No. 589,048, dated August 31, 1897.

Application filed March 14, 1896. Serial No. 583,158. (No model.)

To all whom it may concern:

Be it known that I, CHARLES A. TIMME, a citizen of the United States, residing in the city of New York, in the county and State of 5 New York, have invented certain new and useful Improvements in Electric Dental Furnaces, of which the following is a specification.

This invention relates to an improved electric dental furnace which is intended for use in the manufacture of artificial teeth, bridge-work, and gums, and in which the high degree of heat necessary for the baking of the articles and the melting of the enamel on the 15 same is produced by the electric current that is supplied to suitable heating-plates arranged in the walls of the muffle; and the invention consists of an electric dental furnace which is composed of an exterior casing of 20 refractory material, removable heating-plates arranged at the interior of the muffle, the plates being independently connected with a suitable source of electricity, so that different degrees of heat can be produced at the 25 interior of the muffle, according to the work to be done in the same.

In the accompanying drawings, Figure 1 represents a perspective view of my electric dental furnace. Fig. 2 is a plan view, partly 30 in horizontal section, on line 2 2, Fig. 1; and Fig. 3 is a vertical transverse section on line 3 3, Fig. 2.

Similar letters of reference indicate corresponding parts.

Referring to the drawings, A represents the base of my improved electric dental furnace, which is made either of refractory material or of suitable metal, and which is provided at its rear part with an upright flange a, that 35 extends along three sides of the base A. A muffle B is supported on the base A and arranged so as to abut against the flange a. The muffle B is made of suitable refractory material, preferably of rectangular shape, and 40 provided at its inside with electric heating-plates C C', which are supported at the top and bottom of the muffle and separated from the walls of the same by a layer c of non-conducting material. The electric heating-plates C 45 C' are each formed of refractory material, in which a platinum conducting-wire in serpentine form is embedded while the material is 50

in plastic state. The top and bottom plates may be supported on suitable flanges d d, so as to be readily removed from the muffle for 55 being exchanged or repaired. The side walls may also be provided with similar electric heating-plates D D', as shown in dotted lines in Fig. 3, so that the temperature that is desired to be produced in the muffle can be increased or decreased in whole or at any particular part, according as one, two, or more plates are switched into circuit. The bottom plate C' serves as a support for the objects to be burned in the muffle, such as artificial 65 teeth, bridge-work, gums, &c., made from porcelain and other substances.

By arranging the electric heating-plates independently of the muffle at the inside of the same, the heat of the same is enabled to act 70 directly on the objects to be burned, while at the same time the temperature in the muffle can be raised or lowered by switching in all or a portion of the plates, or the heat can be applied to one or more sides of the objects by 75 switching the upper conducting-plate alone or the side heating-plates, or the upper, side, and bottom plates into the circuit. This arrangement has the advantage that not only the heat in the muffle can be easily regulated, 80 but that larger objects, such as artificial gums, can be burned in the muffle and provided with thicker or thinner coatings of enamel, which can be burned on the objects in a very effective manner.

The front opening of the muffle is closed by 85 a cover B', which is provided with a free packing of insulating material, said cover being provided with exterior stays b', so that it can be supported in contact with the front 90 edges of the muffle. The cover B' is further provided with a peep-opening b², closed by a suitable plug b³.

The front part of the muffle B is surrounded by two metallic straps f f', of which one is 95 provided at one side with two binding-posts f² and at the opposite side with one main binding-post F, while the second strap is provided at one side with one main binding-post F' and at the other side with two binding- 100 posts f³. The current is supplied to the main binding-post F and conducted by the strap f over the binding-posts f² to the wires of the heating-plates C C', if both are used, or the

one or the other only, according as either the top or bottom plates alone is used, in which latter case the ends of conducting-wires are released from the upper or lower binding-post 5 f^2 , respectively. The current is conducted along the wires embedded in the plates C C' and heats said plates to incandescence, passing to the binding-posts f^3 , strap f' , and main binding-post F' back to the battery or other 10 source of electricity. By the electric connection of the main wires with the main binding-posts and of the auxiliary binding-posts with the wires in the plates C C' any one of the heating-plates can be readily placed in 15 circuit and thereby the required degree of heat produced at the interior of the muffle. In case interior heating-plates are used at the side walls of the muffle in addition to the top and bottom plates additional binding-posts 20 for the side plates have to be arranged, to which the ends of the platinum wires are applied, as f^4 f^5 on the strip f , and f^6 and f^7 on the conducting-strip f' , and which are switched into circuit with the main binding-posts, 25 through which the current is supplied. When the burning of the articles in the muffle is completed, the cover is removed, so that access is given to the articles in the muffle. In case any one of the heating-plates should be 30 come defective it can be readily removed from the muffle and either replaced by a new heating-plate or repaired by locating the break in the wire and reconnecting the same. By supplying the muffle with a number of interchangeable heating-plates a dentist is thus 35 enabled to insert a new heating-plate at any time without being required to return the

muffle to the manufacturer for repairs, which is the case when the conducting-wires are embedded in the walls of the muffle itself, in 40 which case it is difficult to locate the break and the use of the muffle rendered impossible until the break has been repaired. This may lead to annoying delays in the work on hand, which is obviated by my improved construction, in which the dentist can readily substitute a new conducting-plate for a defective plate and continue thereby the use of the muffle. 45

The baking of the dental plates is effected 50 at a temperature of 3,500° Fahrenheit or more, and the heating-plates are capable of withstanding such degree of heat.

Having thus described my invention, what I claim as new, and desire to secure by Letters 55 Patent, is—

In an electric dental furnace, the combination of a muffle composed of refractory material, removable independent heating-plates disposed in the walls of said muffle, and composed of refractory material having conductors embedded therein, two separate conductive straps surrounding said muffle near its front end, each provided with a plurality of binding-posts for establishing connection 60 with the electric source and with the heating-plates independently of each other. 65

In testimony that I claim the foregoing as my invention I have signed my name in presence of two subscribing witnesses.

CHARLES A. TIMME.
